Attorney

UNITED STATES PATENT OFFICE

GEORGE W. BIBLE, OF NEW YORK, N. Y.

TRUSS.

SPECIFICATION forming part of Letters Patent No. 373,045, dated November 15, 1887.

Application filed March 23, 1887. Serial No. 232,178. (No model.)

To all whom it may concern:

Be it known that I, GEORGE W. BIBLE, a citizen of the United States, and a resident of New York city, in the county of New York and State of New York, have invented certain new and useful Improvements in Trusses for Rupture, of which the following is a specification.

My invention relates to a novel construction of a truss for ruptures in which is combined several principles never before known in a single device used for this purpose.

Heretofore pads for the truss were made to suit the case, thus necessitating a special pad for each case. As it is seldom I find two ruptures exactly alike, I propose to obviate this necessity, which is also objectionable, by substituting in place of the old truss a device that is capable of being adjusted in a manner to suit any case of rupture on record without removing the pad or separating its parts and locking the pad when the position shall have been obtained.

My invention consists of a rotary staff or other suitable device connected with a device or devices supporting a detachable pad adapted to be adjusted at any angle desired, and mechanism for locking both the rotary staff or other mechanism and the device or devices supporting the pad, all of which will be fully set forth hereinafter.

In the drawings, Figure 1 represents an edge view of the truss device, in which is shown the adjustable and detachable pad. The dotted lines represent the pad in an inclined position. Fig. 2 represents an inverted view of Fig. 1. Fig. 3 represents a plan view of Fig. 1. Fig. 4 represents a sectional view taken on line $x-x$ of Fig. 3. Fig. 5 is a detached view of the device adapted to carry the pad and rotary staff connected with said device. Fig. 6 represents a detached plan view of the device carrying the pad.

Similar letters refer to similar parts throughout the drawings, in which a represents the adjustable and detachable pad held rigid to the plate b by means of the vertical central screw, c . Said plate b is provided with a semicircular flange, b^2 , vertical to the plane of the plate b . The edge of the said flange b^2 is provided with a series of perforations, c , the object of which will be described further on.

The flange b^2 swings upon an arbor, d , which has its bearings in uprights d' , integral with the rotary staff e , the shoulder e' of which rests upon the base-plate A , and the lower portion of the said staff passes through said plate A down to and flush with the lower end of the collar f , integral with the lower plate, B . These plates A and B are arranged on either side of the truss-belt C , and are made secure thereto by means of rivets or other devices.

The hereinbefore-mentioned rotary staff e is provided with a threaded vertical perforation, g , adapted to receive a corresponding threaded screw-stud, h , the point of which engages with the perforations c of the semicircular flange b^2 when holding the pad b in a fixed position.

The periphery of the rotary staff e , near the base thereof, is provided with a series of perforations, i , arranged on the same horizontal alignment and adapted to receive the point of the set-screw i' when holding the staff e in a fixed position.

Modus operandi.—When the nature of the case requires the pad to be adjusted from a horizontal position to that of an incline, and at the same time a rotary motion is necessary for the perfect adjustment, the following operations are deemed necessary to accomplish the desired result: Unscrew the stud h until its point shall have been released from the perforation c of the semicircular flange b^2 , thus enabling the latter to be swung in either direction upon the arbor d , when the desired angle is obtained. Then screw up the stud h until its point shall have entered the perforation or indentation c , when the pad is held in a locked position. It may now be necessary to rotate the pad in order to get it adjusted properly, and in order to do this the set-screw i' is released from the perforations or indentations i , thus enabling the devices carrying the inclined pad to be rotated until the desired position is obtained, and then the set-screw i' is again inserted. Thus locking the staff e in this position, the truss is ready for the patient.

I am aware that many other mechanical devices may be combined to operate and produce the result desired. For instance, in lieu of having the rotary staff as represented in the drawings, I may use a staff with a ratchet on the lower extremity engaging with a pawl or

spring, whereby the same may be locked in position. I may also use, in lieu of the semi-circular flange, a portion of a spur-wheel engaging with pinion or rack-bar; or I may have the semicircular flange held in position by means of a set-screw passing through the upright and against a projection extending from the said semicircular flange. So it will be obvious that many combinations of devices may be used without departing from the spirit of my invention.

Having thus described my invention, what I claim as new, and desire to secure by Letters Patent, is—

15 1. The combination, with a truss for ruptures, of the pad screwed upon the plate provided with the semicircular flange, the whole connected with devices for adjusting the same in any position desired, for the purpose herein set forth.

20 2. The combination, with a truss for ruptures, of the rotary shaft provided with perforations on its periphery near the base thereof, the set-screw corresponding to and engaging

with said perforations, the shoulder to rest 25 upon the plate secured to the belt, the uprights with bearings for an arbor, the threaded vertical perforation, and the corresponding stud engaging therewith, the whole adapted to adjust in any position desired devices carrying a pad, all for the purpose as herein set forth.

3. The combination, substantially as shown and described, consisting of the detachable pad *a*, plate *b*, the vertical screw *c*, the semi-circular flange *b'*, the perforations *c* on the edge of said flange *b'*, the arbor *d*, uprights *d'*, rotary shaft *e*, shoulder *e'*, base-plate *A*, collar *f*, plate *B*, threaded perforation *g*, screw-stud *h*, the perforations *i*, and set-screw *i'*, the 35 whole forming a complete working device.

Signed at New York, in the county of New York and State of New York, this 17th day of November, A. D. 1886.
